UNITED STATES PATENT OFFICE.

GEORGE ROESSLER, OF TOLEDO, OHIO.

MULTIPLE REPRODUCING-MACHINE.

1,302,594.

Specification of Letters Patent.

Patented May 6, 1919.

Application filed September 21, 1917. Serial No. 192,455.

To all whom it may concern:

Be it known that I, GEORGE ROESSLER, a citizen of the United States, and a resident of Toledo, in the county of Lucas and State 5 of Ohio, have invented a certain new and useful Multiple Reproducing-Machine; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 My invention relates to means for reproducing forms from a mold. It has to do with a means for forming shapes, in imitation of patterns. It also has for its object to provide a machine that will automatically 20 produce from patterns, contours of surface like that of the pattern. It particularly has for its object to produce metal molds in multiple of the same or different sizes in imitation of the shape of the 25 surface of a pattern.

Constructions containing the invention may partake of different forms. I have selected one of such constructions as an example and the same is described hereinafter 30 and illustrated in the drawings.

Figure 1 of the drawings is a top view of the construction selected, Fig. 2 is a side view of the construction, and Fig. 3 is an end view of the construction. Fig. 4 is a 35 side view of the pattern shown partly in section to illustrate more clearly some details of construction. Figs. 5 and 6 illustrate sectional views showing end and side views of gear wheel connections of parts of the mechanism. The sections are taken on the broken line 5—6 indicated in Fig. 1. Fig. 7 is a 40 view of the telescoping shaft used for driving the guiding pointer that moves over the pattern. Fig. 8 is a view of the worm 45 gearing for moving the pattern. Fig. 9 illustrates the cutting end of the cutters and Fig. 10 illustrates the pointer used in the machine set for the particular ratio of sizes that is shown in the illustration.

50 1 is the supporting base or bed of the machine having at one end arms or brackets 2 in which is pivoted a shaft 3 to which is connected the guiding and cutting tools of the machine.

55 The guiding tool 4 is secured by means of a suitable chuck to a shaft or spindle sup-

ported in bearings located in the housing 5 that is connected to the arm 6. The arm 6 is connected to the shaft 3 and consequently rotates the shaft 3 in the bearings formed in 60 the ends of the brackets or arms 2. The housing 5 is supported on a bifurcated arm 7 forming an extension of the arm 6. A part of the housing 5 extends through the furcations and is clamped in position by 65 means of a plate 8 and bolts 9 that secures the housing 5 in the position in which it may be adjusted along the extension arm 7. A gear wheel 10 is connected to the pointer 4 for rotation of the pointer. The rotation of 70 the pointer permits it to readily slip along the surface of the pattern and prevents any binding that may occur by reason of the movement of the pointer 4 relative to the pattern, it being held in constant contact with the 75 pattern by the weight of the arms connected to the shaft 3 and the weight of the parts for causing rotation of the pointer and the tools. The gear wheel 10 is preferably a beveled gear wheel and meshes with the beveled gear 80 wheel 11 that is connected to the telescoping shaft 12, the parts of the shaft 12 being slip-keyed together by the key 13 shown in Fig. 7. The outer end of the shaft 12 is supported in a bracket 14 that is secured to the 85 housing 5. It is also supported in brackets 15 and 16 located on the arm 6. The shaft 12 is driven preferably by an electric motor 17 through gear wheels 18. The motor 17 is supported on a bracket 19 that is secured 90 to the arm 6 and to a certain extent its weight counterbalances the weight of the mechanism secured to the shaft 3.

The cutting tools that reproduce the contour of the pattern to be imitated are supported on arms 20 that are keyed to the shaft 3. The arms 20 move with the arm 6 and consequently the cutting tools may be driven from the shaft 12 that is supported in bearings located on the arms 6. The shaft 12 is 95 provided with a beveled gear wheel 21 that meshes with the bevel gear wheel 22 that is keyed to the shaft 23. Bevel gear wheels 24 are also connected to the shaft 23 and operate on bevel gear wheels 25 supported in 100 bearings located and extending transversely through the arms 20. The gear wheels 24 may be located intermediate bracket arms 26 formed on the arms 20 and the bevel gear wheels 25. Cutting tools 27 are connected to 110 the gear wheels 25 and are rotated thereby.

The pointer 4 and the cutting tools 27 are

located so that the axes of their rotation is substantially at right angles to the surfaces of the pattern and molds respectively and thus permits the tools to ride over the surfaces of the pattern and molds in the to and fro movement of the pattern and molds. The nose of the pointer is rounded as is also the end of the cutter. The sizes of the tools are made smaller than the smallest curvature of any part of the surface of the pattern in the one case, and the mold in the other case. Furthermore, the ratio of the sizes of the noses of the pointer and the cutters is the same as that of the distances of the 15 pointer and cutters from the axis of the shaft 3 on which they are supported in order that there may be a true reproduction of the pattern by the cutting action of the cutters, that is, in order that the cutters may follow the varying lines of movements of the pointer in reproducing in the molds the contour of the pattern. Moreover, the 20 lengths of the shanks of the pointer and the cutters may also have the same ratio that exists between the lengths of the arms supporting the pointer and supporting the cutters, in order that the points of contact of the tools may be located at distances from the axis of rotation of the pattern and molds 25 sufficient to insure room for operation of the cutting tools on the side edges of the molds. In the particular form of construction shown in the drawings, the patterns are substantially semi-cylindrical and substantially 30 semi-cylindrical molds are cut from rough castings by the operation of the cutting tools, the machine being particularly designed for forming molds for glass bottles. The axes of the pattern and the molds are 35 located parallel to the axes of rotation of the pattern and molds in order that the pointer which is supported by the telescoping arm 6 and the cutting tools supported by the arms 20 may follow and cut to the very 40 edge of the semi-cylindrical surface. Also in the preferred form of the construction illustrated, the pattern is made very much larger than the molds, which reproduces with greater accuracy the form of the pattern 45 in the molds, the ratio of the dimensions of the pattern to the molds being the same as the ratio between the length of the arm that supports the pointer to the length of the arms that support the cutting tools. Also 50 the distances from corresponding parts of the pattern and the molds from the axes of rotation of the pattern and molds bears the same ratio. The tools thus operate upon the pattern and molds at points that are remote 55 proportionate distances from the axes of rotation of the pattern and molds. The revolving pointer and cutters operating on the pattern and molds thus located remote from the axis of rotation of the pattern and molds holds the tools practically perpendicu-

lar to the inner face of the pattern and molds at all times and readily permits the pointer to move over the patterns and prevents the arms from springing sidewise when working on acute angles. It also permits the use of exceedingly large cutters for cutting the surfaces of the molds. 70

The pattern 28 may be formed of any material such as sheet metal. It is laid in a bed 29 that is supported in a carriage 30 75 having standards 85 in which the bed 29 is pivotally supported. The bed 29 is connected to a worm gear wheel 40 that is rotated by the worm 31 from time to time and previous to the beginning of the cutting operation of the cutters 27 which take place during forward movements of the pattern and molds. The worm 31 is located on a shaft 32 to which is also connected a spiral gear 33. The spiral gear 33 is operated by 80 the spiral gear 34. The spiral gear 34 is slip-keyed on a shaft 35. The shaft 35 is rotated by the spiral gear 36 and the spiral gear 37 with which it meshes. A cog or ratchet wheel 38 is connected to the spiral 85 gear 37. The ratchet wheel 38 is operated by a dog 39 that is pivoted to the carriage 30 by the pivot pin 41. When the carriage 30 moves so as to carry the pointer 4 to the forward end of the pattern and the cutters 27 to the forward ends of the molds, the dog 39 moves the wheel 38 one or two steps according to the position that the dog 39 may be adjusted on the carriage 30. 90

The dog 39 is secured to a block 42 that 100 may be adjusted in any desired position along the carriage 30 by means of a bolt 43.

Rotative movements of the bed 29 are reproduced in the molds 44 but in a ratio that is the same as that existing between the arms 105 6 and 20 that carry the pointer and the cutters. Inasmuch as the points of operation of the cutters are located from the axes of the rotation of the molds and the pointer is located from the axis of the pattern, distances that have the same ratio as the distances of the tools from the axis of the supporting shaft 3, the molds are rotated angularly the same as that of the patterns. Consequently the molds 44 may be rotated by 110 the operations of the shaft 35 which is rotated step by step by the dog 39 operating upon the wheel 38. The shaft 35 is connected through spiral gears 45, 46, shaft 47 and worms located on the shaft 47 to the worm 115 wheels 48. The shaft 47 is supported in the carriage 49 while the gear 45 is slip-keyed to the shaft 35 so that as the carriage 49 to which the molds 44 are connected moves to and fro on the bed 1, the gear 45 slips along 120 a shaft 35. The gears 45 and 34 are located in arms 50 formed on brackets 51 connected to the carriage 30 that supports the pattern and the carriage 49 that supports the molds whereby the gears 34 and 45 are kept in mesh 125 130

with the gears 33 and 46 which are connected to shafts supported in the brackets 51 and are caused to move to and fro with the carriage. The molds are connected with the 5 worm wheels 48 by means of shafts that extend through housings 52 formed on the carriage 49. They are connected to the shafts by depending arms 53 having a suitable face plate 54. The arms 53 locate the molds a 10 short distance below the axes of the shafts passing through the housings 52. This distance is such that the finished surfaces of the molds bears the same ratio to the distance of corresponding parts of the surface of the 15 pattern from its axis of rotation as the distances of the cutting tools from the shaft 3 bears to the distance of the pointer from the shaft 3.

The pattern is supported in the bed 29 and 20 the molds 44 are so located on the plates 54 that the distance of the surface of the pattern from the axis of rotation of its supporting bed 29 has the same ratio to the distance of the finished mold surface from the axis 25 of rotation of the mold that the distance of the adjusted position of the pointer from the shaft 3 has to the length of the arms 20. Thus different sized molds may be produced from the same pattern, or the same 30 sized molds may be produced from different sized patterns, the ratio of the distances of the tools from the shafts 3 being kept the same as the ratio of the distances of the operative ends of the tools from the axis of rotation of the pattern in the one case and the 35 finished surface of the mold in the other case.

The feed of the carriages 30 and 49 must also bear the ratio characteristic of the 40 machine, namely, the ratio of the distance of the pointer from the shaft 3 to the distance of the cutting tools from the shaft 3. The feed of the carriage 30 is produced by the motor 56 suspended on the bed 1 which operates through gear wheels 57, 58 and 59. The gear wheel 59 is keyed to the shaft 60 which is provided with the screw 61 that passes through a depending portion 62 of the bed 30. Rotation of the shaft 60 causes 45 back and forth movement of the bed 30. A different rate of movement is transmitted to the carriage 49 from the motor 56 through gear wheels 58, 63, 64, 65, 66, 67, shaft 68, gear wheels 69, 70, and shaft 71 on which 50 is also located a screw that passes through a part on the carriage 49 to operate the carriage 49 in the same manner as the carriage 30 is operated.

In order to obtain the desired rate of 60 movement of the carriage 49 to the movement of the carriage 30, the gear wheel 63 may be readily removed and an idler 64 of the desired size may be placed intermediate the gear wheels 63 and 65 or the gear wheel 65 64 may be placed on a movable arm 72 that

may be readily swung from between the gear wheels 63 and 64 and replaced when the desired gear wheel 63 has been connected with the gear wheel 58.

The reverse movements of the carriages 70 30 and 49 may be obtained by reversing the current through the motor 56. A pin 73 may be secured to the carriage 30 and a rod 74 may be supported in brackets 75 that are secured to the bed 1. The rod 74 may be 75 moved along the bed 1 by the pin 73 operating on the adjustable fingers 76 that are secured to the rod 74. The rod 74 may be connected to an arm 77 and operates a suitable reversing or a three point switch 78 80 when the pin 73 moves the rod 74. A rheostat 79 may also be connected into the circuit for varying the speed of the motor 56 when the molds are being returned in the manner well known in the art. When the 85 pin 73 strikes one of the fingers 76, it causes movement of the bed 30 away from the shaft 3 and when the pin 73 strikes the other finger 76, it causes movement of the bed 30 toward the shaft 3. Inasmuch as the carriage 49 is moved by the motor 56, the movements of the bed 30 are reproduced in the bed 49 except that the bed will move distances which bears a ratio to the distance that the bed 30 moves that is the same as the ratio 90 of the machine. When the bed 30 returns and just before it strikes the finger 76 nearest the shaft 3, the dog 39 operates on the wheel 38 to cause a short angular rotation of the bed 29 that supports the pattern 28 100 and the plates 54 that support the molds 44 so that upon the return movement of the carriages 30 and 49, the pointer 4 will ride over the same corresponding line on the surface of the pattern that is being cut and 105 finished by the cutters 27 operating on the molds 44. The machine thus continues in its feeding operations until the surface of the pattern has been passed over and the surfaces of the molds have been completed. 110

The cutting tool is provided with a round cutting nose 80, while the pointer tool is provided with a semi-spherical end 81. The noses of the tools bear the same ratio of the machine, that is, the ratio of the distances of the tools from the shaft to which they are connected. The rotation of the cutting tool 27 will describe a semi-spherical surface that will have a radius that bears to the radius of the semi-spherical end of 115 the pointer tool 4 a ratio that is like that of the distances of the tools from the supporting shaft 3. By this means the cutting tools 27 will cut and form finished surfaces exactly like that that the spherical surface 120 of the end 81 of the pointer 4 passes over.

I claim:

1. In a reproducing machine, a guiding pointer having a spherical surface at the end thereof and a cutting tool connected to 130

- the guiding pointer for movement of the tool by the pointer and having a spherical end.
2. In a reproducing machine, a guiding pointer having a spherical surface at its end and a cutting tool connected to the guiding pointer for movement of the tool by the pointer and having a spherical end, the radius of the spherical surface of the pointer having a ratio to that of the surface cut by the tool the same as that of the movement of the pointer to that of the tool.
3. In a reproducing machine, a guiding pointer for a spherical surface at the end thereof and a cutting tool connected to the guiding pointer for movement of the tool by the pointer and having a spherical end, and means for rotating the pointer and the tool.
4. In a reproducing machine, a guiding pointer having a spherical surface at its end and a cutting tool connected to the guiding pointer for movement of the tool by the pointer and having a spherical end, the radius of the spherical surface of the pointer having a ratio to that of the surface cut by the tool the same as that of the movement of the pointer to that of the tool, and means for rotating the pointer and the tool.
5. In a reproducing machine, a guiding pointer, a cutting tool connected to the pointer for pivotal movements about a common axis, a cylindrical pattern, means for supporting the object to be cut, means for angularly rotating and longitudinally moving the said pattern and the object to be cut, the pattern and the object being so supported that the surface of the cylindrical pattern and the cylindrical finished surface of the object are eccentric to the axis of rotation of the pattern and the object, the distance of the axis of the cylindrical pattern from the axis of rotation thereof bearing the same ratio to the distance of the axis of the cylindrical finished surfaces of the object from the axis of rotation of the object that the movement of the pointer has to the cutting tool.
6. In a reproducing machine, a guiding pointer, a cutting tool connected to the pointer, a cylindrical pattern, means for angularly rotating and longitudinally moving the said pattern and the object to be cut, the pattern and the object being so supported that the surface of the pattern and the cylindrical finished surface of the object are eccentric to the axis of rotation of the pattern and the object, respectively.
7. In a reproducing machine, a guiding pointer, an arm for supporting the pointer, a plurality of cutting tools, a plurality of arms supporting the tools, a shaft for connecting the arms for pivotal movements of the pointer and the tools about a common axis, a pattern support and supports for the objects to be cut, means for automatically longitudinally and transversely moving the said supports step by step.
8. In a reproducing machine, a guiding pointer and a plurality of cutting tools, means for connecting the cutting tools with the pointer for pivotal movements of the pointer and the tools, a pattern support and supports for the objects to be cut, means for automatically longitudinally and transversely moving the said support step by step, the longitudinal and transverse movements of the pattern support and the object supports having a ratio that is the same as that of the lengths of the pivotal movements of the pointer and tools respectively.
9. In a reproducing machine, a guiding pointer, an arm for supporting the pointer, a plurality of tools, arms for supporting the tools, a shaft for connecting the arms for pivotal movements of the tools and pointer about a common axis, means supported on the arms for causing rotation of the pointer and the tools.
10. In a reproducing machine, a guiding pointer, a cutting tool connected to the guiding pointer, means for rotating the pointer and the cutting tools, means for angularly and longitudinally moving the pattern and the object to be cut.
11. In a reproducing machine, a guiding pointer, a telescoping arm for supporting the guiding pointer, a plurality of tools, an arm for supporting each of the tools, a shaft for connecting the arms for pivotal movements of the pointer and tools about a common axis, a telescoping shaft for rotating the pointer, a second shaft for rotating the tools.
12. In a reproducing machine, a guiding pointer, a telescoping arm for supporting the guiding pointer, a plurality of tools, an arm for supporting each of the tools, a shaft for connecting the arms for pivotal movements of the pointer and tools about a common axis, a telescoping shaft for rotating the pointer, a second shaft extending transverse the arms and connected to the first shaft for rotating the tools.
- In testimony whereof I have hereunto signed my name to this specification.

GEORGE ROESSLER.
